UNITED STATES PATENT OFFICE

GEORGE E. BRADBROOK, OF NEW YORK, N. Y., ASSIGNOR TO THE C. G. BRAXMAR COMPANY, INC., OF NEW YORK, N. Y., A CORPORATION OF NEW JERSEY

DESIGN FOR A WATCH STAND OR SIMILAR ARTICLE

Application filed November 11, 1929. Serial No. 33,417. Term of patent 7 years.

To all whom it may concern:

Be it known that I, GEORGE E. BRADBROOK, a citizen of the United States of America, residing at New York, in the county of New York and State of New York, have invented a new, original, and ornamental Design for a Watch Stand or Similar Article, of which the following is a specification, reference being made to the accompanying drawing, forming part thereof.

The drawing illustrates in perspective view a watch stand or similar article, showing my new design.

I claim:

The ornamental design for a watch stand or similar article, as shown.

GEORGE E. BRADBROOK.
